UNITED STATES PATENT OFFICE.

JOSEPH A. FIRSCHING, OF UTICA, NEW YORK.

DYEING-MACHINE.

1,356,059.

Specification of Letters Patent. Patented Oct. 19, 1920.

Application filed March 5, 1919. Serial No. 280,723.

To all whom it may concern:

Be it known that I, JOSEPH A. FIRSCHING, a citizen of the United States of America, and resident of Utica, in the county of Oneida, in the State of New York, have invented new and useful Improvements in Dyeing-Machines, of which the following, taken in connection with the accompanying drawings, is a full, clear, and exact description.

This invention relates to certain improvements in dyeing machines and is particularly designed for intermittently applying dye to traveling yarn, thread or the like. The object of the invention is to produce an efficient device of quite simple construction for dyeing spaced lengths of yarn as wound from one bobbin to another by wiping the yarn across the dye carrying applying element without independent movement of the yarn either toward or from said element and preferably the parts are so formed and arranged as to give the yarn a rolling movement while in contact with said element whereby the dye is applied more uniformly throughout the entire circumference of the yarn.

Other objects and advantages relate to the details of construction of the dye carrying applying element as will more fully appear from the following description taken in connection with the accompanying drawings in which,—

Figure 1 is a top plan view of a portion of a dye tank equipped with my invention.

Fig. 2 is a cross section on line 2—2, Fig. 1.

Fig. 3 is a cross section on line taken at right angles to Fig. 2.

Fig. 4 is a view similar to Fig. 2 of a modified form of machine.

Fig. 5 is a view similar to Fig. 3, of the machine illustrated in Fig. 4.

As shown in Figs. 1 to 3 inclusive, the machine comprises a tank —1— formed of a metallic cylinder —2— having its ends closed by caps —3— combined with lock-nuts —4— and interposed packing —5— insuring a liquid tight joint. Arcuate portions of the wall of cylinder —2— are cut out or removed and substantially flat plates —6— are fitted into the recesses so formed and have flanges —7— fitting the adjacent portions of the wall of the cylinder —2— and secured thereto as by screws —8—.

The plate —6— is provided with a groove

or channel —9— in its upper exposed face and this groove preferably as shown extends from one end along one edge of the plate for a short distance, then diagonally across the plate to a point spaced from the opposite end thereof and then along the opposite edge to said opposite end, for a purpose hereinafter described. The plate —9— is provided with a central opening forming a communicating passage way between the said groove or channel and the interior of the tank —1—. The plate may be formed or provided with substantially circular pins —10— rising in the channel —9— to guide the yarn through the diagonally disposed portion of the channel.

For the purpose of intermittently applying dye to the traveling yarn, a rotary element —11— is provided, formed with one or more (in this instance eight) radially projecting dye carrying applying parts —12—, such parts move successively through the opening in plate —6— into the channel —9— for contact with the moving yarn as the said element is rotated.

As shown the element —11— is built up from a series of dye absorbent disks —13—, —14— and —15—, the disks —13— and —14— serving only to assist in uniformly supplying dye to the dye applying parts —12— which are formed in connection with and in this illustration as a part of the central disk —15—. In other words the central disk —15— may be formed in much the shape of a gear, the projecting teeth constituting the dye carrying applying parts. The disks —13—, —14— and —15— are held in assembled position by a pair of oppositely disposed plates —16— and —17—, one of said plates as —16— provided with an axially projecting flange —18— extending through the absorbent disks and the plate —17— and having its end threaded for interlocking engagement with nut —19—. The element so formed may be carried by sleeve —20— mounted upon shaft —21— having its opposite ends journaled respectively in arms —22— and —23— carried by plate —6—.

The arms —22— and —23— may if desired be pivotally carried from downwardly projecting lugs —24— formed in connection with the plate —6—. The plates —16— and —17— are preferably in the form of gears adapted to mesh with gears —25— and —26— constituting the confining plates of a dye feeding roller —27— built up in much

the same manner as element —11— and forming a substantial counterpart of said element. The absorbent dye carrying disks —28—, —29— and —30— are each provided 5 with peripheral cross grooves or recesses forming with and constituting a counterpart of the projecting teeth or parts —12— of disk —15— and as disk —15— meshes primarily with the said disk —29—, dye will 10 be uniformly applied to the dye carrying applying parts —12—. The driving of disk —15— might be effected by its meshing relation with disk —29— but preferably perhaps, as shown, the additional positive drive 15 is provided through the medium of plates —16— and —17— and —25— and —26— respectively. The plates —16— and —17— do not project beyond the periphery of disks —13— and —14— whereas plates 20 —25— and —26— have teeth projecting outwardly from the greatest diameter of the disks —25— and —26—. As shown the dye feeding roller —27— built up as described may be of considerably less diameter than 25 the element —11— so that the element —11— is rotated at a slower speed. The feeding roll —27— may be mounted upon shaft —31— driven through any suitable connections and preferably by the mechanism 30 described in my application Ser. No. 280,722, filed March 5, 1919, whereby the speed of said shaft varies with the speed of the traveling yarn.

The operation will be readily understood. 35 As the element —11— rotates, the dye carrying applying parts will be successively and at spaced intervals moved through the opening in plate —6— into contact with the yarn traveling through the channel —9—. The 40 yarn will be wiped across the moving part or tooth and thereby dye will be applied to the yarn. The movement of the yarn across the element —11— diagonally of plate —6— and at an angle other than a right angle 45 with the axis of element —11— will cause the dye applying part —12— to give to the yarn a rolling motion as it is wiped across the said part whereby the dye will be substantially uniformly applied to the entire 50 circumference of the yarn. Guides —32— and —33— may be provided for causing the yarn to move through channel —9— at the desired elevation.

In Figs. 4 and 5, I have illustrated a 55 modified form of device in which the element —11— is mounted directly upon shaft —31— and the feeding roller —30— is omitted, the dye carrying applying parts picking up their own dye from the body of the same 60 contained by tank —2—. In this construction the element is formed of the three absorbent disks —13—, —14— and —15—, the latter having the projecting dye applying parts —12—. These disks are confined by a

pair of oppositely disposed plates —32— 65 and —33— mounted upon a sleeve —34— having a flange —35— in contact with plate —32— and a washer —36— in contact with plate —33—, the parts being held in this assembled position by nut —37— having a 70 threaded relation with the end of sleeve —34— adjacent the washer —36—. The sleeve —34— may as shown be set-screwed or otherwise secured to shaft —31— for rotation therewith. This structure operates 75 to apply dye to the traveling yarn in substantially the same manner as the structure of the former figures. It is found however, that the feed and application of the dye is perhaps somewhat less uniform than when 80 the feeding roller —27— is utilized.

It will be noted that the structure in essence consists of a series of spaced dye carrying applying parts, mounted for rotation upon a common axis and adapted to be 85 brought successively into wiping contact with the traveling yarn. The speed of rotation of element —11— and the spaced distance of the dyeing parts —12— may be so regulated and predetermined as to dye the 90 yarn in desired lengths spaced a uniform predetermined distance apart, upon condition that the speed of shaft —31— is synchronized with the speed of the traveling 95 yarn. Otherwise the dyed lengths and the 100 space between the dyed lengths will vary in accordance with the variations in speed of the yarn assuming that the speed of element —11— is substantially constant. My 105 invention includes both methods of operation as the structure is adapted for either.

In the operation of the structures illustrated it is a practical essential that the yarn be maintained in a proper position relatively to the periphery of the dye applying elements and to the effective operating surface of said elements. If the yarn moves longitudinally in such a position that the dye applying elements project radially of the wheel too far beyond the yarn the lateral 110 thrust when the element comes in contact with the yarn will tend to break the latter. For this reason I have provided an adjustable supporting means for the yarn so that its position may be accurately and delicately 115 predetermined and varied to hold the yarn in the proper position.

This means as illustrated comprises a pair of hook shaped members positioned upon opposite sides of the rotary dye applying 120 parts —12— and preferably these members are jointly formed of a single piece of wire bent to desired shape so as to form the oppositely disposed hook shaped parts —38— and the intermediate integral part —39—. 125 The yarn supporting device so formed has its opposite ends carried in any suitable adjustable manner as from post 40 supported

from plate 6. Post 40 may carry a pair of spaced nuts —41— between which a pair of clamping plates —42— are secured, such plates having concavities at their opposite ends for gripping the ends of the yarn supporting member. By adjusting nuts —41— along post —40— the proper relative position of the yarn supporting member may be determined. Although the dye applying parts —12— may be of various shapes, my experience leads me to believe that preferably they should be parts of spheres of relatively small diameter.

Although, I have shown and described a particular construction of apparatus including a specific built up construction of element —11—, I do not desire to limit myself to the structure shown or to the particular form or relation of the parts as illustrated. Various changes may be made in the details of form, construction and arrangement without departing from the invention as set forth in the appended claims.

What I claim is:—

- 25 1. In a dyeing machine a rotary gear shaped absorbent disk and means for supplying dye to the disk.
2. In a dyeing machine a rotary gear shaped absorbent disk and a gear shaped 30 roll for feeding dye to the disk.
3. In a winding and dyeing machine a rotary gear shaped absorbent disk and ad-

justable means for holding yarn in predetermined position relative to the disk.

4. In a winding and dyeing machine a 35 gear shaped absorbent disk, a gear shaped dye feeding roll, for rotating and feeding dye to said disk and adjustable means for holding the yarn in predetermined position relative to the disk. 40

5. In a winding and dyeing machine a rotary gear shaped absorbent disk and means for moving yarn longitudinally across the periphery of said disk at an angle other than a right angle with the axis of rotation of 45 the disk.

6. In a winding and dyeing machine, a plurality of absorbent disks coaxially arranged, a plurality of spaced dye-applying elements projecting radially from the exterior of said disks, means for securing the disks together, and means for supplying dye to the disks. 50

7. In a winding and dyeing machine a rotary wheel including a plurality of radially projecting dye applying elements, a rotary dye feeding element, and intermeshing gears on said wheel and said feeding element. 55

In witness whereof I have hereunto set my hand this 26th day of February, 1919.

JOSEPH A. FIRSCHING.
